UNITED STATES PATENT OFFICE.

JOHN WEBER, OF WEST ALLIS, WISCONSIN.

VEHICLE SIGNAL.

Application filed April 27, 1927. Serial No. 186,898.

This invention relates to improvements in vehicle signals, and more particularly to an arm or semaphore type of signal for the purpose of indicating an intention on the part 5 of the vehicle driver to turn either to the right or left or to stop.

It is the primary object of the present invention to provide a vehicle signal of the semaphore type which will fold very compactly into a space provided therefor in a casing adjacent a vehicle body post, and when so folded the signal will not be at all visible.

A further object of the invention is to 15 provide a signal of the class described including an arm and a hand at the outer end thereof, the hand being constructed so that portions thereof will fold together when in inoperative position to conserve space.

20 A further object of the invention is to provide a folding signal in which the parts will not rattle when in folded position within their enclosure.

25 A further object of the invention is to provide a vehicle signal having manually operated mechanical means for projecting the arm from its enclosure and for unfolding the hand.

30 A further object of the invention is to provide a vehicle signal which is of very simple construction, is strong and durable, is easily operated, and is well adapted for the purpose described.

35 With the above and other objects in view the invention consists of the improved vehicle signal, and its parts and combinations as set forth in the claims, and all equivalents thereof.

40 In the accompanying drawing in which the same reference characters indicate the same parts in all of the views:

45 Fig. 1 is a longitudinal sectional view of the signal enclosure with the signal shown in extended signaling position, parts being shown in section;

Fig. 2 is a view of the enclosure with the signal therein in folded hidden position, parts being shown in section;

50 Fig. 3 is an enlarged detail sectional view showing a drum; and

Fig. 4 is an edge view of the signal enclosure with the signal arm therein and on a smaller scale.

55 Referring now more particularly to the drawing, it will appear that the numeral 8 indicates a portion of a vehicle body post

which is provided with a metal casing and extending vertically thereadjacent. A signal arm, designated 10, is pivotally mounted, as at 11, at its inner end portion within the 60 casing 9.

The arm 10 is formed in two sections 12 and 13 and when said arm is extended horizontally, as shown in Fig. 1, said sections are held in separated position by a flat spring 65 14. The arm sections are prevented from separating beyond a predetermined distance by complementary stop means 15 at the outer end portions of the arm sections.

Both of the arm sections are formed at 70 their outer end portions with pairs of fingers, those of the arm section 12 being designated 16 and the fingers of the arm section 13 being designated 17. The section 12 also has pivotally attached thereto a thumb 18 and the pivotal connection is effected by means of a hook 19 formed at the inner end portion of the thumb engaged with a notch 20 in an elongated flange plate 21 secured to the edge 75 of the arm section 12. An inner end portion of the thumb has pivotally secured thereto a link 22 which is pivotally secured at its other end portion to the arm section 13, as at 23. The thumb is adapted to move through an elongated slot 24 provided therefor in the 80 flange plate 21 and the outer edge portion of the thumb has secured thereto a cover plate 25 to close the slot 24 when the parts are within the casing. In the latter position, the flange plate 21 serves to close the casing 85 opening, as shown in Fig. 4, protecting the parts therewithin from weather.

The mechanism for operating the arm includes a link 26 pivotally connected at its outer end portion with the arm section 12 90 by means of a rivet 28 extending through a slot 29 in the other arm section. The inner end portion of said link is pivotally connected to a lever 27 mounted fast on a transversely projecting shaft 30, said shaft also having fast thereon a pulley 31. A drum 32 is carried by a stud shaft 33 at the lower end portion of the casing and said shaft also has removably held on the squared portion 33' by means of a nut 34 an operating crank 100 35. Both end portions of a cable or belt 36 are secured to the drum, as at 37, and said cable extends around the drum and upwardly over a freely mounted pulley 38 at the upper portion of the casing, around the pulley 31, over an adjacent idler pulley 39 and downwardly to the drum 32, bearing 110

against a small lower pulley 40. Hence, by turning the drum in one direction, by means of the crank, the cable will be wound, turning the pulley 31 and shaft 30 to operate the lever 27 and link 26 in a suitable direction to extend the arm 10 to the horizontal position shown in Fig. 1. A reverse movement of the crank will wind the cable to cause a reverse movement of the pulley 31, lever 37 and link 26 to lower the arm to the vertical position within the casing shown in Fig. 2.

The link 26, in moving in either direction, frictionally engages a spring 41 depending from the casing, the lower portion of the spring having a lug portion 41' which rides along a recess 42 on the edge of the link 26. The engagement between the spring and link prevents abrupt movements of the signal arm. Also, when the spring lug 41' engages a shoulder 42' at the end of the recess 42, the parts will be frictionally engaged so that the arm is extended at a forty-five degree angle.

If desired, the crank 35 may be removed from the lower stud shaft 33 and mounted on the shaft 30 carrying the pulley 31 and the signal operated from this position.

In operation, the signal arm is extended to the horizontal position for signaling purposes and when so extended the arm sections will separate and the thumb will be moved to a projecting position. When the arm is swung into the casing the arm sections will overlap and the thumb will fold inwardly, as shown in Fig. 2. In this position the parts will occupy a minimum amount of space and will not be visible and the casing will be closed against weather by the plates 21 and 25.

From the foregoing description it will be seen that the improved signal is of simple and novel construction, and is well adapted for the purposes set forth.

What I claim as my invention is:

1. A vehicle signal, comprising a casing, a sectional signal arm pivotally mounted at one end within the casing, and a foldable element connected to the free end portion of one of the arm sections.

2. A vehicle signal, comprising a casing, a sectional signal arm pivotally mounted at

one end within the casing, each section thereof being formed at its free end with fingers, and a movable finger hinged to one of said sections and operatively connected with the other section. 55

3. A vehicle signal, comprising a casing, a sectional signal arm pivotally mounted at one end within the casing, a foldable element connected to the free end portion of one of the arm sections, and means for moving the signal arm from a vertical position within the casing to an extending horizontal position and vice versa. 65

4. A vehicle signal, comprising a casing, a signal arm pivotally mounted at one end portion within the casing, said arm being formed of a pair of longitudinally overlapping sections foldable one upon the other, means for automatically unfolding said sections with respect to each other when the arm is moved outwardly of the casing, and a foldable element hingedly attached to one of said arm sections and connected with the other of said sections whereby said element will be unfolded with respect to the arm when the arm sections are unfolded with respect to each other. 70

5. A vehicle signal, comprising a casing having a side opening, a signal arm pivotally mounted at one end portion within the casing, means for moving the signal arm from a vertical position within the casing through the side opening to a horizontal position, said arm being formed of a pair of longitudinally overlapping sections foldable one upon the other, each section being formed at its free end with finger portions, means for automatically unfolding said sections with respect to each other when the arm is moved outwardly of the casing, a thumb member hingedly connected to one of the sections, a link connection between the thumb and the other section for unfolding the thumb with respect to the arm when the arm sections are unfolded with respect to each other, and a plate secured to an edge of the arm for covering said casing opening when the arm is within the casing. 80 85

In testimony whereof, I affix my signature.

JOHN WEBER.
